FRANGIBLE BOTTLE CAP

Amos R. Mattis, Providence, R. I.

Application September 23, 1949, Serial No. 117,382

2 Claims. (Cl. 215—46)

1

My invention relates to frangible bottle caps and comprises a modification of the standard type of metal cap member for bottles having a circular crown and a cylindrical rim portion depending from the circumferential edge thereof adapted to underlie the lower bottle rim of a standard soda bottle, beer bottle, milk bottle, etc. When attached these standard metal caps are put on at the factory by the manufacturer and it is impossible to remove them without using a special bottle opener. I am aware that others have provided frangible bottle caps, but so far as I am aware these have required pulling a strip of metal from the crown and rim to remove them; a very difficult operation for the average user.

An object of my invention is to remove a strip from such a bottle cap throughout a portion of the crown and through the rim thereof and secure the upper portion of said removed strip to a separate disc member and secure the depending rim portion to the edges of the slot formed in the rim by its removal with readily frangible soft solder which even a child can break.

A further object of my invention is to provide a frangible bottle cap of pleasing appearance generally similar to that of a standard bottle cap.

When using standard metal caps, it is very often possible to remove them and still replace them so that the contents of the bottles may be substituted.

A further object of my invention is to provide a frangible bottle cap which will positively prevent any substitution as the bottle cap is completely destroyed when used or tampered with.

A further object of my invention is to provide a frangible bottle cap for bottles so close in size and arrangement to that of a standard metal cap that there will be no protruding parts in the way of a standard capping machine, permitting the bottlers to cap the bottles with the use of this standard bottling equipment.

A further object of my invention is to provide a frangible bottle cap which is also leak proof.

A further object of my invention is to provide a bottle cap employing only one additional piece of metal to that used in standard bottle cap members and one which may be readily fabricated and quickly assembled.

A further feature of my invention relates to

the method I employ for making such a frangible bottle cap.

These and such other objects of my invention as may hereinafter appear will be best understood from a description of the accompanying drawings which illustrate an embodiment thereof.

In the drawings, Fig. 1 is a perspective view of a frangible bottle cap constructed in accordance with my invention.

Fig. 2 is a cross-sectional view of my improved bottle cap shown in Fig. 1.

Fig. 3 is a perspective view showing my frangible bottle cap in use in a closed position on top of a bottle.

Fig. 4 is a perspective view illustrating my invention after the bottle cap has been suitably broken to remove it from the top of the bottle.

Fig. 5 is a perspective view illustrating the bottle cap after the step of cutting two spaced slits from the edge of the crown diametrically across the crown and through the adjacent rim portion has been performed thereon.

Fig. 6 is a perspective view illustrating the steps of forming a separate disc of standard size to the crown of the cap having a transverse slot therein, cutting the free strap end shown in Fig. 5 and bending it upwardly to pass through said transverse disc slot, soldering the remaining crown portion of the strip cut off from said two slits to the lower edge of said disc member so that the depending rim portion may be soldered to the edges of the rim slot.

Fig. 7 is a perspective view illustrating how the disc is pivoted to a flat position on the crown so that the lip may be pushed up through said slot and may be bent downwardly thereon as shown.

Fig. 8 is an exploded perspective view of the various parts including the disc, the cut crown, and rim of the cap member, the waterproof disc and the cork disc.

In the drawings, wherein like characters of reference generally indicate like parts throughout, Fig. 1 generally indicates a frangible bottle cap constructed in accordance with my invention. Said bottle cap comprises a metal cap member 11 having a circular crown 12 and a circumferential rim 14 depending from the circumferential edge thereof. The lower portion of said circumferential rim is adapted to underlie the rounded bottle rim when attached and is preferably beaded as.

shown for this purpose. The cap member 11 is constructed out of resilient metal so that rim 14 will hug the bottle rim in use to retain the cap thereto. In accordance with my invention, said cap member 11 has the spaced slits 16 extending from an edge 18 of the crown, diametrically across the crown and through the adjacent portion 20 of the rim, providing a flat strip 22 extending substantially to the center of the crown and terminating in a bent-up flat lip 24 and providing a slot 26 extending from said lip through the remainder of said crown portion and rim.

I also provide a strap portion 28 of the size and shape of the remainder of the slot 26 including the crown portion 30 thereof and the rim portion 32 thereof having a flat upper portion 34 and a depending rim portion 36 soldered to the edges of said rim slot 32.

It is obvious that said strap portion 28 comprises the remainder of the cut away strip 22.

I also provide a disc 38 of substantially the size of said crown having a transverse slot 40 substantially centrally thereof to receive said upper strap lip 24, bent at 42 over said disc 38 to retain said disc thereon with said disc 38 soldered to the flat portion 34 of said strap 28 along a radial line normal to said transverse lip slot 40. I also provide a flexible waterproof disc 44 having a crown 46 of substantially the size of the cap rim 14. Said waterproof disc is constructed of any suitable material such as Lucite, acetate resin, or otherwise, and the crown portion 46 suitably adhered to the crown portion 12 of the metal cap 11 by glue or any suitable adhesive. I also provide a cork disc 50 of similar size suitably attached by glue or any other suitable adhesive to the lower surface of the crown of the waterproof disc 46.

My invention also includes a novel method of making a bottle cap which comprises stamping from any suitable strip or otherwise, of metal, plastic, etc. material, a cap member 11 having a circular crown 12 and a cylindrical rim 14 depending from the circular edge thereof, cutting spaced slits 16 in any suitable manner by any suitable type of cutting mechanism from an edge 18 of the crown diametrically across the crown and lower adjacent rim portion 20 providing a flat strip 21 extending from the edge 18 of the crown, across said crown and down said rim portion 20, cutting off said strip slightly beyond the center of said crown as at 23 to provide a strip portion 28 of the size and shape of the edges of said slot 30 having a flat upper portion 34 and a depending rim portion 36, bending the tip of the cut-off strap portion upwardly as at 24 to form a flat bent-up flat lip 24, stamping a disc 38 from flat metal stock similar to that employed when making the cap 11 of substantially the size of the crown 12 of said cap and providing it with the transverse slot 40 substantially centrally thereof in any suitable type of stamping operation, soldering the said portion 34 of said strip portion 28 to the under surface of said disc 38 radially aligned with said transverse slot 40 and suitably soldering the depending rim portion 36 to the edges of the rim slot 20, bending said disc 38 downwardly so that said lip 24 extends through the disc slot 40 and bending said lip 24 downwardly on said disc as at 42, forming a flexible waterproof disc 44 having a similar crown 46 and depending rim 48 and adhering the crown thereof to the lower surface of the crown 12 of said cap member 11 and adhering a cork disc 50 of

similar size to said crown 46 to the lower surface of the crown 46 of said waterproof disc.

It is apparent that I provide a novel type of frangible bottle cap which may be made of one extra piece to that employed in a standard bottle cap and one which may be very easily assembled. The bottle cap which I have shown in the figures is sold to the trade just as standard types of bottle caps, and may be used by the bottling trade with the standard type of capping machines to cap liquid in bottles. The lip 24 is readily bendable and may be, if desired, lifted up to a vertical position preparatory to opening. This is not absolutely necessary, however, as the disc 38 may be grasped by the finger directly opposite the slot 30 and lifted upwardly lifting the lip 24 outwardly as shown in Fig. 4 as to pivot the disc upwardly to pull the strap 28 upwardly to separate the depending rim 36 thereof from the edges of the slot 20 formed in the rim, the soft solder employed for holding the said depending rim portion 36 to the edges of the slot 20 readily yielding and separating for this purpose. As shown in Fig. 4 the remains of the broken bottle cap may then be readily lifted over the top of the bottle 52, and thrown away. The hand 54 may grasp the bottle and the other hand 56 may grasp the disc to lift it up and break the edges of its rim portion from the edges of the rim slot 20 for taking my improved cap off the top of the bottle, as my cap when once broken cannot be used again.

I have provided a structure which cannot be tampered with to substitute the contents of the bottle with which it is used.

It is apparent that I have provided a novel type of readily frangible bottle cap and an improved method of its manufacture with the advantages described above.

40 It is understood that my invention is not limited to the specific embodiment shown or method described and that various deviations may be made therefrom without departing from the spirit and scope of the appended claims.

45 What I claim is:

1. A frangible bottle cap comprising a metal cap member having a circular crown and a cylindrical rim portion depending from the circumferential edge thereof, adapted to underlie the 50 rounded bottle rim when attached, said cap member having spaced slits extending from an edge of the crown diametrically partly across the crown, providing a flat strip extending substantially to the center of the crown and terminating in a short bent-up flat lip, the crown having a slot extending from said lip through the remainder of said crown portion and rim, a strap portion of the size and shape of the remainder of said slot having a flat upper portion and a 55 depending rim portion soldered to the edges of said rim slot, and a disc of substantially the size of said crown, having a transverse slot substantially centrally thereof receiving said upturned strip lip bent over said disc to retain said 60 disc thereon with said disc soldered to the flat portion of said strap along a radial line normal to said transverse lip slot, a flexible waterproof disc having a similar crown and depending rim portion adhered to the lower surface of the crown 65 70 of said cap member and a similar cork disc secured to the lower surface of the crown of said waterproof disc.

2. A frangible cap comprising a metal cap member having a circular crown and a cylindrical rim portion depending from the circumferential

edge thereof, adapted to underlie the rounded bottle rim when attached, said cap member having spaced slits extending from an edge of the crown diametrically partly across the crown, providing a flat strip extending substantially to the center of the crown and terminating in a short bent-up flat lip, the crown having a slot extending from said lip through the remainder of said crown portion and rim, a strap portion of the size and shape of the remainder of said slot having a flat upper portion and a depending rim portion soldered to the edges of said rim slot, and a disc of substantially the size of said crown, having a transverse slot substantially centrally thereof receiving said upturned strip lip bent over said disc to retain said disc thereon with said disc soldered

to the flat portion of said strap along a radial line normal to said transverse lip slot.

AMOS R. MATTIS.
